SURFACE-PROTECTIVE APPARATUS

Russell S. Colley, Kent, Ohio, assignor to The
B. F. Goodrich Company, New York, N. Y., a
corporation of New York

Application March 9, 1938, Serial No. 194,843

8 Claims. (Cl. 244—134)

This invention relates to surface-protective apparatus and is especially useful for preventing accumulation of ice upon surfaces such as the leading edges of airfoils and other surfaces of 5 aircraft. The invention relates especially to an improved inflatable shoe or container for the purpose of changing the contour of the surface to break accumulated ice for removal of the latter in the air stream.

10 In some installations the wing or other airfoil is of considerable thickness at its root or inboard end and tapers in thickness rapidly toward the tip where the airfoil is comparatively thin. For most effective operation it is desirable that the 15 inflatable shoe be of a construction such that the shape-changing function of the shoe is not lessened in effectiveness by the dimensional differences of the airfoil.

The chief objects of the invention are to provide 20 a surface-protective shoe of improved construction, to provide a shoe of the inflatable type in which the construction and operation in portions thereof is suited to the dimensional characteristics of the airfoil for most effective operation, to provide improved means for securing the shoe to the airfoil, especially so that the shoe may be mounted in a condition of strong tension, to provide an improved shoe attachment by 25 which mounting of the shoe in a curved condition about the tip of the airfoil is facilitated, and to provide durability of construction and convenience of assembly.

These and further objects will be apparent from a description reference being had to the 30 accompanying drawing in which:

Fig. 1 is a plan view, with parts broken away, of an airplane having protective shoes mounted at the leading edges of its wings and horizontal stabilizer, which shoes are constructed according to and embodying the invention.

Fig. 2 is a plan view with parts broken away of a shoe before its application to the airfoil.

Fig. 3 is a section taken along the line 3—3 of Fig. 2.

45 Fig. 4 is a perspective view with parts broken away and sectioned, the view being taken at the line 4—4 of Fig. 1.

Fig. 5 is a section taken along the line 5—5 of Fig. 4.

50 Fig. 6 is a horizontal section of a portion of the shoe.

Fig. 7 is a view like Fig. 5, but showing a modified construction.

Fig. 8 is a view like Fig. 7 but showing a fair-

ing element mounted on the airfoil in lieu of the protective shoe.

The invention is illustrated as applied to an 5 inflatable shoe for preventing accumulation of ice upon the leading edges of airplane wings and other airfoils. In some types of aircraft, especially in thick-winged monoplanes, the wing, and sometimes other airfoil surfaces taper in thickness very rapidly toward their tips so that if the 10 inflatable shoe comprises inflatable tubes of uniform width extending throughout the leading edge the shoe will be very effective to break up ice by changing of its surface in the thick portions of the leading edge where there is an extensive surface for ice accumulation, but the 15 shoe will be less effective in the region of the wing tip, where the tubes are not so well adapted to alter the relatively small narrow surface presented at the leading edge. The invention 20 includes the feature, among other things, of overcoming this difficulty.

Referring to Fig. 1, an airplane 10 comprising 25 wings 11, 11 and horizontal stabilizers 12, 12 has inflatable shoes 13 and 14 mounted at the leading edge of each wing, and a shoe 15 mounted 30 at the leading edge of each horizontal stabilizer. The shoes 13, 14 may be spaced apart along the leading edge of the wing to leave a space therebetween for a landing light or other structure 35 in the wing.

The shoe 13, which extends over a considerable portion of the span of the wing including a thick portion thereof and a thin wing tip portion, is 40 of the improved construction illustrated most clearly in Figs. 2 to 6.

The shoe preferably is elastic and adapted to be mounted in a condition of stretch upon the airfoil. To this end the shoe comprises a plurality of united elastic elements, including a bottom sheet 16 and a top sheet 17 between which 45 are disposed a plurality of inflatable tubes to constitute the shoe and inflatable container. The sheets and tubes preferably are of rubber to provide the desired extensibility with air-tightness.

The shoe is an elongate structure preferably 50 tapering in width in accordance with the tapering thickness of the airfoil. Throughout the greater portion of the wider end of the shoe the inflation and deflation is effected by means of a plurality of the inflatable tubes, preferably 55 three or more, of substantially uniform cross-section throughout their lengths, these tubes being indicated at 18, 19 and 20.

In continuation of the tubes 18 to 20 at the narrow end of the shoe is provided a pair of in- 55

latable tubes 21 and 22 lying along side each other and having their adjacent walls disposed in a sinuous manner, as is shown most clearly in Fig. 2, to assure effective changing of the 5 shape of the leading edge surface at the wing tip despite the thinness of this portion of the wing. Connections 23, 24 and 25 may be provided at the inboard ends of the tubes 18, 19 and 10 20 for the purpose of inflating and deflating these tubes in groups through suitable fluid-controlling apparatus. A rubber filler strip 26a may be disposed between the tubes 21 and 22.

The tubes 21 and 22 may be inflated and deflated independently of the tubes 18 to 20, if desired, but it is preferred to provide connections so that the straight tubes and the curved tubes can be inflated and deflated in groups. As is shown most clearly in Fig. 6, the curved tubes 21 and 22 are in communication with the central 20 straight tube 19 so that these are inflated and deflated as a group, preferably in alternation with the group consisting of straight tubes 18 and 20, the two groups being inflated and deflated alternatively as by any suitable valve mechanism, not 25 shown, to change the surface shape for breaking up accumulated ice.

Suitable fabric tapes 26, preferably bias-laid for stretchability, may be provided at adjacent tube margins for the purpose of reinforcement. 30 Inasmuch as the shoe is mounted under tension and is operated under tension it is desirable to provide strips 27, 27 of stretchable fabric extending across the tubes at spaced apart positions along the shoe to increase tear resistance locally 35 so that a puncture of the rubber will not enlarge and spread undesirably along the shoe, which reinforcing feature is described and claimed in the co-pending application of Myron L. Taylor, Serial No. 160,105, filed August 16, 1937.

40 At the upper and lower margins of the shoe, attaching means are provided for mounting the shoe upon the airfoil. As the same form of attachment may be used at both margins, only the upper one need be described. A fabric strip 28 45 is provided along the margin of the shoe and united to the rubber thereof, the strip being folded to accommodate a metallic strip element 29 extending throughout the margin of the shoe. Preferably the metallic strip element 29, which 50 may be of any desired shape, but preferably is in the form of a flat or oval wire, is loosely mounted in the fabric 28 so that the marginal material of the shoe may be slipped or gathered along the wire 29 in the region of the tip of the wing for 55 the purpose of permitting the shoe to be fitted around the wing tip to protect the surface. This construction permits attachment of the shoe without undesirable wrinkles, the tensioned condition of the shoe being utilized to avoid wrinkles in 60 the gathered material despite the curving of the shoe margin at the wing tip.

Bevelled rubber filler strips 30, 30 may be provided at the margin of the inflatable tubes and fabric strips 27, and the parts of the shoe structure 65 preferably are united by vulcanization of the rubber, providing permanent adhesion.

For attaching the shoe to the airfoil, screws 31, 31 are disposed through the shoe structure just inside the wire 29, the screws being tapped into 70 hollow threaded rivets 32, 32 set into the metal surface or other structure of the airfoil, and the arrangement being such that the wire 29 is adapted to bear against the screws 31, 31 to maintain the shoe in a condition of tension between 75 its upper and lower margins. A fairing strip 33

may be provided over the margin of the shoe at the wire 29 to provide a smooth surface for the airflow, and to assist in attaching the shoe, and this strip may also be held in place by the screws 31, 31.

In the embodiment of Fig. 7 the metal skin of the airfoil 40 is provided with a step or offset at 41 adapted to receive the inflatable shoe so that the latter in its deflated form will provide a leading edge of the desired normal shape. A hold down strip 42 may be provided at the margin to clamp down the margin of the shoe and hold it in place by means of screws 31, 31. When the shoe is removed, as during the summer season, a strip 43 of rubber or other suitable material (Fig. 8) 15 may be substituted for the shoe at the offset to provide a flush surface.

Variations may be made without departing from the scope of the invention as it is defined in the following claims.

I claim:

1. Apparatus for preventing ice accumulation upon a surface comprising an elastic shoe adapted to be mounted upon said surface, means for securing the shoe upon the surface in a condition of tension comprising a metallic strip element mounted in the shoe structure at its margin and means on the surface against which a side surface of the said strip element is adapted to bear to maintain the shoe under tension.

2. Apparatus for preventing ice accumulation upon a surface comprising an elastic shoe adapted to be mounted upon said surface, means for securing the shoe upon the surface in a condition of tension comprising a metallic strip element mounted in the shoe structure at its margin and means on the surface against which the said strip element is adapted to bear to maintain the shoe under tension, said metallic strip element being bendable and mounted for sliding movement in the margin of the shoe for conforming the shoe to a curved surface.

3. Apparatus for preventing accumulation of ice upon the leading edge of an airfoil comprising an elongate, elastic shoe adapted to be mounted upon said leading edge, means for securing the shoe upon said leading edge in a condition of tension transversely of the shoe comprising a metallic strip element mounted in the margin of the shoe, and means on the airfoil against which a side surface of the said strip is adapted to bear to maintain the shoe under tension.

4. Apparatus for preventing accumulation of ice upon the leading edge of an airfoil including the tip thereof, said apparatus comprising a flexible shoe adapted to be mounted upon said leading edge and about said tip, means for securing the shoe to the airfoil including a metallic strip element mounted loosely in a margin of the shoe to facilitate adjustment of the material of the latter to curve the shoe about said tip, and means on the airfoil for engaging said strip element.

5. An airfoil assembly comprising an airfoil, means for preventing accumulation of ice upon the leading edge of said airfoil comprising a flexible shoe mounted upon said leading edge, means for securing the shoe in such relation comprising a metallic strip element mounted in a margin of the shoe and attaching means on the airfoil extending through the flexible material of the shoe and abutting a side surface of said strip element for holding the shoe in place.

6. An airfoil assembly as defined in claim 5 comprising a fairing strip overlying the margin

of the shoe and metallic strip element and detachably held in place by the said attaching means.

7. An airfoil assembly as defined in claim 5 in which the airfoil is formed with an offset portion providing a recess in which the margin of the shoe is disposed and secured providing a substantially flush surface in the region of said margin.

10 8. Apparatus for preventing accumulation of ice on aircraft comprising an elongate, elastic sheet of rubber-like material, a plurality of distensible tubes of substantially straight walls mounted side by side along a portion of the 15 length of said sheet, a pair of distensible tubes of varying cross-section mounted side by side

along another portion of said sheet in continuation of the first said tubes and with large portions of each opposite small portions of the other, said sheet and tubes constituting a unitary structure, means for conducting pressure fluid 5 into and venting it from said tubes, and means for mounting said elastic sheet upon an aircraft surface with the sheet held stretched in the direction crosswise of said tubes, the mounting means comprising a metallic strip secured to the 10 sheet along a margin thereof and a plurality of elements secured to the aircraft and positioned to be abutted by a side surface of said strip to maintain the sheet in the stretched condition.
